DESIGN FOR A DRESS

Maxwell Richter, New York, N. Y.

Application October 6, 1945, Serial No. 122,617

Term of patent 3½ years

(Cl. D3—26)

To all whom it may concern:

Be it known that I, Maxwell Richter, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

I claim:

The ornamental design for a dress, substantially as shown.

MAXWELL RICHTER.
